UNITED STATES PATENT OFFICE.

FREDERICK W. WURSTER, OF BROOKLYN, NEW YORK.

VEHICLE-SPRING COUPLING.

SPECIFICATION forming part of Letters Patent No. 350,282, dated October 5, 1886.

Application filed April 3, 1886. Serial No. 197,619. (No model.)

To all whom it may concern:

Be it known that I, FREDERICK W. WURSTER, of Brooklyn, in the county of Kings and State of New York, have invented a new and Improved Vehicle-Spring Coupling, of which the following is a full, clear, and exact description.

This invention relates to the construction and arrangement of the clips, yokes, and clip-plates by which a carriage-spring is ordinarily attached to the body of the vehicle, its object being to facilitate the attachment of the spring and improve the construction of the coupling.

The invention consists in the combination, with a clip-plate provided with countersinks to receive the closed ends of the U bolts or clips, of yokes uniting the arms of the clips below the spring, and of clamping-nuts on the clip-arms, all as hereinafter described.

The invention also consists in details of construction and combinations of parts, as herein specified.

Reference is to be had to the accompanying drawings, forming a part of this specification, in which similar letters of reference indicate corresponding parts in all the figures.

Figure 1 is a perspective view of my improved spring-coupling. Fig. 2 is a central longitudinal section of the same attached to the wagon-body. Fig. 3 is a cross-sectional view on the line x x, Fig. 2.

The clip-plate A, which is attached to the wagon-body C by bolts passed through the bolt-holes a, in the usual manner, is formed on its upper side with the elongated transverse countersinks B, and on its lower side with corresponding beads, D, so as not to decrease the strength of the clip-plate. The countersinks B are formed with apertures b at each end, through which are passed the parallel arms E' of the U bolts or clips E, the cross-bars of which are received in the countersinks B, so as to be flush with the upper surface of the clip-plate A. The arms E' of each clip embrace the sides of the plates F, constituting the spring, and are united at their lower ends by the yoke G, between which and the bead D

the spring-plates F are firmly clamped by means of the nuts H, screwed on the outer ends of the arms E'. The upper plate, F, of the spring is held in position by the pointed stud d on each bead D being forced into its upper side, and between the adjacent spring-plates are placed the cross strips or leaves I, held in place by their end recesses engaging the opposite clip-arms E', the slight play between the spring-plates thus provided for making an extremely live spring. With this construction the clip-plate A, carrying the spring, can be attached directly to the vehicle-body without previously preparing recesses therein, as has been the usual custom, to receive the clips, which have heretofore projected above the clip-plate. Further, the upper spring-plate, F, being fulcrumed, as it were, on the rounded beads D, it is allowed more play, thus increasing the elasticity of the spring.

The combination of clip-plates, clips, and yokes in a spring-coupling I do not broadly claim as my invention; neither do I claim the interposition of the leaves I between the spring-plates F; but,

Having thus fully described my invention, what I claim as new, and desire to secure by Letters Patent, is—

1. A vehicle-spring coupling composed of the clip-plate A, having elongated countersinks B and corresponding beads, D, the clips E, received in the countersinks B and embracing the spring, the yokes G, and the clamping-nuts H, substantially as specified.

2. The combination, with the vehicle-body, of the clip-plate A, having elongated countersinks B, beads D, and pointed studs d, the clips E, received in the countersinks B, the spring-plates F, embraced by the clip-arms E' and separated by the leaves I, the yokes G, and the nuts H, substantially as shown and described.

F. W. WURSTER.
